Jesse C. Johnson INVENTOR
BY Victor J. Evans
ATTORNEY

UNITED STATES PATENT OFFICE

JESSE C. JOHNSON, OF DELRAY, FLORIDA, ASSIGNOR TO JOHNSON HELICOPTER TOY AEROPLANE CORPORATION, OF NEW YORK, N. Y., A CORPORATION OF DELAWARE

TOY HELICOPTER AEROPLANE

Application filed April 26, 1929. Serial No. 358,412.

This invention relates to a toy helicopter aeroplane, the general object of the invention being to provide the toy aeroplane with the usual tractor propeller and a horizontally arranged propeller under each wing, with electric means for driving the propellers, thus providing a toy which will afford amusement to children and adults and which will be instructive in illustrating the lifting force of the helicopter propellers and the pulling force of the tractor propeller.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:

Figure 1 is a front view of the invention.

Figure 2 is a top plan view, with parts in section.

Figure 3 is a vertical sectional view through the front part of the device, with parts in elevation.

Figure 4 is a view similar to Figure 2, but showing a modification.

In these views, the numeral 1 indicates the fuselage of the toy aeroplane and 2 the wings thereof. An electric motor 3 is located in the front part of the fuselage and acts to drive the shaft 4 to which the propeller 5 is attached. A helicopter propeller 6 is arranged under each wing and has its vertically arranged shaft 7 extending into the wing, the shaft being journaled in a depending bracket 8 attached to the wing and in a part of the wing. The upper end of the shaft, which is located in the wing, has fastened thereto a beveled gear 9. A shaft 10 passes through the fuselage into the wings and has beveled gears 11 at its ends which mesh with the gears 9. Beveled gears 12 connect this shaft with the rear part of the shaft 4 which is driven from the motor.

As will be seen, each propeller 6 is of greater length than the width of each wing and

said propellers 6 act to lift the plane vertically while the propeller 5 acts to pull the plane forwardly, the three propellers being driven from the single motor. If desired, however, a second motor 13 may be used to drive the shaft 10, as shown in Figure 4.

The plane is suspended from any suitable support by the tubular member 14 which has its lower end connected with the fuselage and the conductors 15 for supplying current to the motor may pass through this member. The plane is provided with the usual landing gear 16.

From the foregoing it will be seen that I have provided an attractive toy which will both amuse and instruct children as well as adults, for upon the starting up of the motor, or motors, the propellers 6 will act to lift the toy off the surface on which it rests and the propeller 5 will pull the toy forwardly and thus the toy will revolve in a circle and this circle will be gradually increased as the plane picks up speed. Of course, the propellers 6 will help to drive the plane forwardly as the plane assumes an inclined position as it passes around its circular path.

As before stated, the toy will be instructive in illustrating the action of the helicopter propellers in lifting the plane vertically and the pulling action of the propeller 5 so that the toy is instructive as well as amusing.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:

A toy aeroplane comprising a hollow body, an electric motor mounted in the body upon the upper side of the bottom thereof and near the forward end thereof and including a shaft extending forwardly through the forward end of the body and rearwardly beyond the motor, a propeller mounted upon the forward end of the shaft, a bevel gear mounted upon the rear end of the shaft, a flexible current conductor connected with the upper side

of the body in rear of the motor and above
the rear end of the said shaft, to supply cur-
rent to the motor, hollow wings extending
from each side of the body, a shaft, rotatably
5 mounted in the wings, a bevel gear upon the
shaft meshing with the bevel gear upon the
motor shaft, shafts journaled in the under
sides of the wings and having their upper
10 ends extending into the wings, a bevel gear
upon the upper end of each of said shafts,
bevel gears upon the outer ends of the second
mentioned shafts, meshing with the gears
upon the last mentioned shafts and helicop-
15 ter propellers mounted upon the lower ends
of the last mentioned shafts.

15 In testimony whereof I affix my signature.
JESSE C. JOHNSON.
